UNITED STATES PATENT OFFICE.

ELIAS C. WALKER, OF CALMAR, IOWA.

POSTAL DATE-HOLDER.

SPECIFICATION forming part of Letters Patent No. 391,216, dated October 16, 1888.

Application filed December 2, 1886. Serial No 220,484. (No model.)

To all whom it may concern:

Be it known that I, ELIAS C. WALKER, of Calmar, in the county of Winneshiek and State of Iowa, have invented a new and Improved 5 Postal Date-Holder, of which the following is a full, clear, and exact description.

This invention relates to a cheap, durable, and efficient box or holder for postal or other interchangeable dates.

10 The invention consists in the construction and arrangement of parts, as will be hereinafter more fully described, and specifically pointed out in the claim.

Reference is to be had to the accompanying 15 drawings, forming a part of this specification, in which similar letters of reference indicate corresponding parts in both the views.

Figure 1 is a plan view of my improved postal date-holder, the outer cover being removed 20 and the inner cover being broken away to disclose the interior construction; and Fig. 2 is a face view of the holder.

In the drawings, A represents a circular box, that is preferably made of metal, and that is 25 divided into annular chambers B and C by walls or flanges D and E, that are concentric with the edge of the box. Each of these annular chambers B and C is divided into a number of minor compartments, within which the 30 type-blocks may be placed, these compartments being preferably formed by a metallic strip bent so as to extend across the chamber, then along one of the defining walls of the chamber, then again across the chamber and along 35 the other defining-wall, and so on around the chamber, these strips being shown at F and G, the arrangement being such that each of the annular chambers of the box is divided into a number of compartments.

40 The cover H is centrally apertured to receive a retaining-screw, I, the inner end of

which engages with a nut, K, that is fixed to the bottom of the box, and this cover H is formed with two apertures, L and M, the aperture L being arranged to register with the 45 compartments of the chamber B, while the aperture M is arranged to register with the compartments of the chamber C, the cover being free to turn upon its central connection with the box.

In addition to the main cover H, I prefer to employ an auxiliary cover, N, that is held to place above the cover H by the screw I, and arranged so that it may be turned to close the aperture M, in which position it is shown in 55 Fig. 2; or it may be moved to close the aperture L, this latter position being indicated by dotted lines in Fig. 2.

The several dates are placed in the compartments in the manner shown in Fig. 1, after 60 which any date may be removed from the box by turning the cover so that one of its openings is above the date required, when, if the box is turned upside down, the date will fall out. In changing the dates, the one in use is 65 returned to its position and the cover is turned so that the proper aperture will register with the required date.

Having thus fully described my invention, I claim as new and desire to secure by Letters 70 Patent—

The combination, with the casing having two circular concentric series of type-spaces, and a revoluble cover having two apertures corresponding with the type-spaces, of an auxiliary 75 cover concentric with and revolving upon the main cover and adapted to close either one of its apertures, substantially as set forth.

ELIAS C. WALKER.
